UNITED STATES PATENT OFFICE.

STANLEY S. BORUSIEWSKI, OF PORTLAND, OREGON.

SAW-SETTING DEVICE.

Application filed October 1, 1921. Serial No. 504,752.

To all whom it may concern:

Be it known that I, STANLEY S. BORUSIEWSKI, a citizen of the United States, residing at Portland, in the county of Multnomah and State of Oregon, have invented certain new and useful Improvements in Saw-Setting Devices, of which the following is a specification.

This invention relates to certain improvements in saw setting devices, and more particularly to a hand tool type of the same adapted for the accurate setting of the teeth of saws throughout a comparatively wide range of sizes thereof.

The principal object of the invention is to provide for a device or tool of the class mentioned, and one of an extremely simple, comparatively inexpensive, and durable construction, such as is capable of easy manipulation for the simultaneous setting of two contiguous teeth of a saw in each operation thereof.

With the foregoing and other objects in view, the invention resides in the certain novel and useful construction and arrangement of parts as will be hereinafter more fully described, set forth in the appended claims, and illustrated in the accompanying drawings, in which:

Figure 1 is a side elevation, partly in section of a preferred embodiment of the device or tool, the section or portion thereof being taken on the line 1—1 of Figure 2,

Figure 2 is a top plan view;

Figure 3 is a transverse section taken on the line 3—3 of Figure 2;

Figure 4 is a fragmentary detail, partly in section, of the free end portion of one of the setting plungers,

Figure 5 is a fragmentary sectional detail of the inner of the setting plungers and the adjacent connected end portion of the actuating plunger thereof,

Figure 6 is an elevation of the securing pin for the spring tensioning means of the said inner setting plunger, and,

Figure 7 is an elevation of the washer interposed between the spring tensioning means and the securing pin thereof.

Referring to the drawing, wherein similar characters of reference designate corresponding parts throughout the several views thereof, the device or tool comprises namely, a frame portion 10 integrally formed with

13 extending in opposite directions to either side of the transverse center of the frame portion 10, and offset one with respect to the other to either side of the longitudinal center thereof, and an operating handle 14 arranged to be manipulated for the simultaneous actuating plungers 12 and 13 for the setting of two contiguous teeth of a saw at one time.

The frame portion, designated generally by the numeral 10, comprises a casting formed with an inner relatively narrow portion 15, integrally connecting the handle 11, an intermediate transversely and vertically 70 enlarged portion 16, and an outer reduced and substantially conical end portion 17, the latter being slightly offset to one side of the longitudinal center of the frame portion 16. The intermediate enlarged portion 16 of the 75 tool frame 10 is slotted as at 18 upwardly of its lower side and on the transverse center thereof for the reception therein of the toothed edge of a saw (not shown), and formed in the center of the upper face of this 80 portion of the frame is an opening or recess 19, which is preferably rectangular in plan and has the slotway 18 opening upwardly of the transverse center thereof. Extending centrally through the reduced end portion 85 17 of the frame 10 and opening into the recess 19 is a circular bore 20 in which is slidably mounted the outer of the setting plungers 13, which has its inner and active 90 end portion formed to provide a saw tooth 95 engaging head 13'. The opposite wall of the recess 19 is provided with a bore 21 in which is slidably mounted the inner of the setting plungers 12, and similarly the end of the same projecting into the recess 19 is 95 formed to provide a saw tooth engaging head 12', the heads 12' and 13', of the plungers 12 and 13, being normally at rest to either side of the saw receiving slotway 18.

The outer end of the plunger 13 is projected for a suitable distance beyond the forward end of the conical portion 17 of the frame 10, and is formed with a reduced threaded end portion 22 for the engagement 100 thereon of a member or pivot bracket 23 and a clamping nut 24 for securing the member or bracket 23 in position, the latter having its free end arranged for pivotal engagement in the bifurcated end 25, of a 105 connecting member 26, and on the pivot pin 27 carried thereby. The member 26 has

its end opposite to the end 25 thereof formed to provide a threaded bore or socket, in which is secured the complementally threaded end of an actuating rod 28, which, in 5 turn, has its opposite end pivoted as at 29 in a bifurcated offset portion 30 formed on the upper edge of the operating handle 14 and outwardly from the inner end of the latter, which is pivoted on a pivot pin 31 10 secured in and extending between a pair of oppositely disposed cheeks or side walls 32 formed on the upper side of the connected end portion of the fixed handle 11.

The inner narrow portion 15 on the frame 15 10, between the enlarged portion 16 and the walled portion 32 of the handle 11, is formed to provide a recess 33 through which the setting plunger 12 passes, and in which is positioned a device for the tensioning of the 20 operating mechanism of the tool. This tensioning device comprises a coiled spring 34 positioned on the portion of the plunger 12 passing through the recess 33, and has one of its ends bearing directly against 25 the opposed face of the inner wall of the portion 15 of the frame, and its opposite end arranged in abutting relation to a washer 35, which is also positioned on the setting plunger 12, the washer 35, in turn, abutting 30 a pin 36 disposed in an opening 37 formed diametrically of the plunger 12, which pin 36, in its turn, abuts the wall 38 of the recess 33. As shown, the washer 35 is formed to provide a straight side edge 35' 35 arranged to overlie the bottom wall of the recess 33, whereby the same is prevented from turning within the latter and on the plunger 12.

The free end of the setting plunger 12, 40 opposite to its headed end 12', is formed to provide a reduced extension 39, which is engaged in a socket formed in the opposed end of an actuating plunger 40, the latter being slidably supported in the wall 38 and 45 is operable for the setting movement of the plunger 12 against the tension of the spring 34, upon the manipulation of the operating handle 14, the free end of the plunger 40 having bearing contact with a cam surface 50 41 formed on the inner end of the handle 14 at a point below the pivot 31 thereof.

In the use and operation of the device or tool thus provided, the slotway 18 of the same is engaged over the toothed edge of a 55 saw (not shown) with the heads 12' and 13', of the plungers 12 and 13, disposed in alignment with the first two contiguous teeth thereof, when upon gripping the handles 11 and 14, and pressing downwardly 60 on the operating handle 14 the plungers 12 and 13 will be forced toward and past one another the required distance to either side of the slotway 18 as to properly set the teeth being operated on, during which movement 65 of the plungers 12 and 13, the spring 34

will be compressed under the direct action of the actuating plunger and the cam end 41 of the operating handle 14 forcing against the same, and, upon the release of the handle 14, the spring 34 will expand in 70 a manner to force the plungers 12 and 40 back to normal position for the starting of the next setting operation. In the passing back of the operating plunger 40, the same, through its bearing action on the 75 cam surface 21, swings the handle 14 upwardly on its pivot 31, so that its movement is transmitted to the plunger 13, through the medium of the rod 28 and its parts 26 and 23 connecting the plunger 13, and acts to 80 withdraw the same simultaneously to its normal starting position. The movement of the parts in the instance of the setting operation is accomplished by the cam surface 41, of the operating handle 14, acting directly against the actuating plunger 40 and the saw setting plunger 12 aligned therewith, which action, is accompanied by a pulling action of the handle 14 on the rod 28, its connections 26 and 23, and the setting 90 plunger 13, whereby the latter moves simultaneously with and in the direction opposite to that of the plunger 12, as has been hereinbefore explained.

From the foregoing, it will be readily apparent that, while a preferred embodiment of the device or tool has been described and illustrated herein in specific terms and details of construction, arrangement and operation of the several parts thereof, various 100 changes in and modifications of the same may be resorted to without departing from the spirit of the invention, or the scope of the claims appended hereto.

Having thus fully described the invention 105 what is claimed, is:—

1. In a device for the purpose set forth, a stationary handle, a frame projecting forwardly therefrom and integral therewith and having transverse means for the reception of the toothed edge of a saw, an operating handle extending into and having its inner end pivoted to said stationary handle, said operating handle having a cam at its inner end, a pair of oppositely disposed and longitudinally movable setting elements disposed at right angles with respect to said means and slidably mounted in said frame, one of said elements engaged and operated by said cam when said operating member 110 is shifted inwardly, and means carried on the outer end of the other of said elements and pivotally connected to said operating member for operating the last mentioned element simultaneously with the other elements.

2. In a device for the purpose set forth, a stationary handle, a frame projecting forwardly therefrom and integral therewith and having transverse means for the recep- 130

- tion of the toothed edge of a saw, an operating handle extending into and having its inner end pivoted to said stationary handle, said operating handle having a cam at its 5 inner end, a pair of oppositely disposed longitudinally movable setting elements disposed at right angles with respect to said means and slidably mounted in said frame, one of said elements engaged and operated 10 by said cam when said operating member is shifted inwardly, and adjustable means carried on the outer end of the other of said elements and pivotally connected to said operating member for operating the last 15 mentioned element simultaneously with the other elements.
3. In a device for the purpose set forth, a stationary handle, a frame projecting forwardly therefrom and integral therewith 20 and having transverse means for the reception of the toothed edge of a saw, an operating handle extending into and having its inner end pivoted to said stationary handle, said operating handle having a cam at its 25 inner end, a pair of oppositely disposed and longitudinally movable setting elements disposed at right angles with respect to said means and slidably mounted in said frame, one of said elements engaged and operated 30 by said cam when said operating member is shifted inwardly, a pivoted bracket secured to the outer end of the other of said elements, and a connecting member attached to said bracket and pivotally connected to 35 said operating member whereby the last mentioned element is simultaneously operated with the other of said elements when the operating handle is shifted inwardly.
4. In a device for the purpose set forth, 40 a stationary handle, a frame projecting forwardly therefrom and integral therewith and having transverse means for the reception of the toothed edge of a saw, an operating handle extending into and having its inner end pivoted to said stationary handle, said operating handle having a cam at its 45 inner end, a pair of oppositely disposed longitudinally movable setting elements disposed at right angles with respect to said means and slidably mounted in said frame, one of said elements engaged and operated 50 by said cam when said operating member is shifted inwardly, a pivoted bracket secured to the outer end of the other of said elements, and a connecting member 55 adjustably connected to said bracket and further pivotally connected to said operating member whereby the last mentioned element is operated simultaneously 60 with the other element when the operating handle is shifted inwardly.
5. In a device for the purpose set forth, a stationary handle, a frame projecting forwardly therefrom and integral therewith 65 and having transverse means for the reception of the toothed edge of a saw, an operating handle extending into and having its inner end pivoted to said stationary handle, said operating handle having a cam at its 70 inner end, a pair of oppositely disposed and longitudinally movable setting elements disposed at right angles with respect to said means and slidably mounted in said frame, one of said elements engaged and operated 75 by said cam when said operating member is shifted inwardly, means carried on the outer end of the other of said elements and pivotally connected to said operating member for operating the last mentioned element simultaneously with the 80 other elements, and means mounted in the frame and associated with that element actuated by the cam for restoring said elements to normal position when the operating handle is released.
6. In a device for the purpose set forth, a stationary handle, a frame projecting forwardly therefrom and integral therewith and having transverse means for the reception of the toothed edge of a saw, an operating handle extending into and having its inner end pivoted to said stationary handle, said operating handle having a cam at its 85 inner end, a pair of oppositely disposed longitudinally movable setting elements disposed at right angles with respect to said means and slidably mounted in said frame, one of said elements engaged and operated by said cam when said operating member is shifted inwardly, adjustable means carried on the outer end of the other of said elements and pivotally connected to said operating member for operating the last mentioned element simultaneously with the 90 other elements, and means mounted in the frame and associated with that element actuated by the cam for restoring said elements to normal position when the operating handle is released.
7. In a device for the purpose set forth, a stationary handle, a frame projecting forwardly therefrom and integral therewith and having transverse means for the reception of the toothed edge of a saw, an operating handle extending into and having its 95 inner end pivoted to said stationary handle, said operating handle having a cam at its inner end, a pair of oppositely disposed and longitudinally movable setting elements disposed at right angles with respect to said means and slidably mounted in said frame, one of said elements engaged and operated by said cam when said operating member is shifted inwardly, adjustable means carried on the outer end of the other of said elements and pivotally connected to said operating member for operating the last mentioned element simultaneously with the 100 other elements, and means mounted in the frame and associated with that element actuated by the cam for restoring said elements to normal position when the operating handle is released.

ments when the operating handle is shifted inwardly, and means mounted in the frame and associated with that element actuated by the cam for restoring said elements to normal position when the operating handle is released.

8. In a device for the purpose set forth, a stationary handle, a frame projecting forwardly therefrom and integral therewith and having transverse means for the reception of the toothed edge of a saw, an operating handle extending into and having its inner end pivoted to said stationary handle, said operating handle having a cam at its inner end, a pair of oppositely disposed longitudinally movable setting elements disposed at right angles with respect to said means and slidably mounted in said frame,

one of said elements engaged and operated by said cam when said operating member 20 is shifted inwardly, a pivoted bracket secured to the outer end of the other of said elements, a connecting member adjustably connected to said bracket and further pivotally connected to said operating member 25 whereby the last mentioned element is operated simultaneously with the other element when the operating handle is shifted inwardly, and means mounted in the frame and associated with that element actuated by the cam for restoring said elements to normal position when the operating handle is released.

In testimony whereof, I affix my signature hereto.

STANLEY S. BORUSIEWSKI.
